UNITED STATES PATENT OFFICE.

JOHN C. BLAIR, OF HUNTINGDON, PENNSYLVANIA.

ENVELOPE.

SPECIFICATION forming part of Letters Patent No. 240,646, dated April 26, 1881.

Application filed February 26, 1881. (No model.)

To all whom it may concern:

Be it known that I, JOHN C. BLAIR, a citizen of the United States, resident at Huntingdon, in the State of Pennsylvania, have invented 5 certain new and useful Improvements in Envelopes and Blotters; and I do hereby declare the following to be a full, clear, and exact description of the invention, such as will enable others skilled in the art to which it appertains 10 to make and use the same, reference being had to the accompanying drawings, and to letters or figures of reference marked thereon, which form a part of this specification.

Figure 1 is a representation of a plan view 15 with the cover thrown back. Fig. 2 is a view with the cover closed, and Fig. 3 is a sectional view.

This invention relates to improvements in 20 devices for receiving paper or materials for writing.

The invention consists in an envelope having a sheet of blotting-paper attached thereto, as hereinafter fully described, and particularly 25 pointed out in the claim.

25 In the annexed drawings, A represents an envelope having a size suitable for the contents to be placed therein. Instead of the ordinary flap for sealing, the envelope has a short lip, *a*, turned down and gummed.

30 B is a sheet of blotting-paper of a size a little less than that of the envelope. One edge, *b*, of this paper is glued to the lip *a*, and, cov-

ering the mouth of the envelope, hangs over the front of the same. This forms a convenient and handy receptacle for holding and carrying papers. The blotter being stiff acts as a firm cover, preventing the contents from falling out, and is always at hand for use in blotting.

The blotter may have anything printed upon its exposed face, whereby the device can be used as a cheap and taking means of advertisement.

This construction is intended to be used in all sizes and kinds of envelopes, including extra large for law business and insurance forms, medium for legal papers, still smaller for newspaper and envelopes, long and narrow size for notes and checks, and ordinary commercial size suitable for a variety of uses.

I am aware that an envelope having a back of sized paper with the opposite side of unsized or blotting paper, is not new, and I make no broad claim thereto.

What I claim is—

An envelope, A, having the sheet of blotting-paper B attached to the short flap *a*, substantially as and for the purposes set forth.

In testimony whereof I affix my signature in presence of two witnesses.

J. C. BLAIR.
